UNITED STATES PATENT OFFICE.

WILFRED VALLIER, OF PONTIAC, MICHIGAN.

STARTING-CRANK.

1,104,851.

Specification of Letters Patent.

Patented July 28, 1914.

Application filed December 15, 1911. Serial No. 665,940.

To all whom it may concern:

Be it known that I, WILFRED VALLIER, a citizen of the United States of America, residing at Pontiac, in the county of Oakland 5 and State of Michigan, have invented certain new and useful Improvements in Starting-Crank, of which the following is a specification, reference being had therein to the accompanying drawings.

10 The invention relates to starting cranks for explosion engines and has among the objects thereof to provide a construction of crank which will automatically and practically instantaneously uncouple from the engine shaft in case of back firing, to provide such a type of crank that may be readily adapted for use with engines of various sizes, and further to produce a construction which may be easily and cheaply manufactured and which is reliable and efficient.

20 Other objects of my invention will more fully hereinafter appear.

The invention resides in the peculiar construction, arrangement and combination of 25 parts as hereinafter described and particularly pointed out in the claims.

In the drawings,—Figure 1 is a vertical central section through a crank embodying my invention; Fig. 2 is a horizontal section 30 therethrough; Fig. 3 is a section on line $x-x$ — x Fig. 1; and Fig. 4 is a fragmentary side elevation.

A represents the engine shaft and B the shaft of the starting crank, the shaft portion C of which is journaled as is usual in a spring-pressed bearing D. The shaft portion C is formed of a tubular member within which is positioned for a limited longitudinal sliding movement a member E provided with a head F fitting the bore of the tubular member and having a shank G which is arranged for longitudinal travel within a bearing member H.

I is a pin extending through the head F and having the projecting ends thereof engaging slotted portions J in the tubular shaft, the pin being held in proper relation to the head by means of a lock screw K.

L and M are complementary dogs arranged upon opposite sides of the member C and journaled on a stub shaft N carried thereby. This stub shaft is preferably in the form of a bolt extending transversely of the member C adjacent its inner end and is held against rotation in relation to the same, as by means of a key O.

The complementary dogs are normally maintained in a horizontal position by means of light tension springs P which yieldably press the rear ends of the dogs 60 against stops Q, Q', each of the springs having their opposite ends anchored respectively to the stub shaft and the dog. By this arrangement the members L and M are held against movement in one direction by 65 the stops but may be rocked in the opposite direction against the tension of the springs P. The stops however are so arranged as to permit the member L to rock in a direction opposite from the movement of the 70 member M. In the horizontal position of the complementary dogs the pin I is yieldably held in engagement with segmental bearings R and S, formed in the inner ends of the dogs L and M, by a coil spring T 75 which surrounds the shank G and has its opposite ends abutting against the head F and the bearing member H. When the dogs are horizontally arranged the outer ends thereof are positioned in operative relation 80 to the engine shaft, and may be engaged with the usual clutch teeth U thereof by pushing the crank inward.

V represents the handle for the crank shaft which is fixedly secured thereto in any 85 suitable manner, as by a key W. and H' designates a button or knob upon the end of the shank G which is extended without the bearing H.

With the parts so far described, when it 90 is desired to start the engine the operator pushes the starting crank inward until the outer ends of the complementary dogs engage the clutch teeth on the end of the engine shaft and then rotates the crank in a 95 direction to effect a forward rotation of the engine shaft, the tension of the spring T being sufficient to hold the pin I in engagement with the bearings R and S and prevent rocking of the dogs during this operation. If the engine properly starts the cam faces X of the clutch teeth U will act upon the cam portions Z on the ends of the dogs to force the crank rearward and uncouple the crank from the engine shaft as is usual. 100 However, in case the engine back fires the sudden impact upon the outer ends of the dogs will rock the latter, moving the inner ends of the dogs out of engagement with the pin I against the tension of the spring T. 110 After the bearings R and S are moved out of engagement with the pin the member E

is pressed inward by the spring T, positioning the pin I in the path of the inner ends of the dogs as shown in dotted lines in Fig. 4, which prevents the return of the dogs to their horizontal position. The tripping of the dogs and the locking of the same in their inoperative position is practically instantaneous upon back firing and occurs without even the slightest backward rotation of the crank shaft.

To return the parts to their normal relation the member E is pulled outward through the medium of the knob H' against the tension of the spring T a sufficient distance to move the pin I out of the path of the inner ends of the dogs, permitting the latter to be moved to their horizontal position by the springs P.

As the pressure required for retaining the pin I in engagement with the segmental bearings during cranking will necessarily vary with the size of the engine the bearing member H has an adjustable screw-threaded engagement with the tubular shaft, which permits the tension of the spring T to be regulated. I also provide means for retaining the member H in its various positions of adjustment preferably in the form of a spring-pressed detent A' on the member H which detachably engages longitudinal grooves B' in the threads on the tubular shaft. When the detent is positioned within one of the grooves B' the member H is locked against movement from normal strains but may be adjusted by applying sufficient force to move the detent out of the groove against the tension of its spring.

The construction shown and described is one that can be cheaply manufactured, is simple, efficient and positive in its operation. But although the crank illustrated is the preferred form of my invention, I do not desire to limit my protection to the specific structure shown in the drawings.

What I claim as my invention is,—

1. The combination with the shaft of an explosion engine, of a crank shaft, and means for rotatably coupling said shafts together upon a forward rotation of the crank shaft adapted to automatically and practically instantaneously uncouple said shafts upon a backward rotation of the engine shaft comprising a rockable dog carried by the crank shaft having one end positioned in operative relation to the engine shaft and provided with a bearing at its opposite end and a spring-pressed member having a bearing for engaging said first-mentioned bearing in the normal relation of the parts, said spring pressed member acting automatically to retain the dog in an inoperative position upon the uncoupling of the shafts.

2. The combination with the shaft of an explosion engine, of a tubular crank shaft,

a stub shaft carried by the tubular shaft, a dog journaled on said stub shaft and having one end positioned to engage the engine shaft, a spring-pressed member slidably engaging the tubular shaft, and a detachable pin-and-socket engagement between the spring-pressed member and said dog.

3. The combination with the shaft of an explosion engine, of a tubular crank shaft, a stub shaft carried by the tubular shaft, a dog journaled on said stub shaft and having one end positioned to engage the engine shaft, a spring-pressed member slidably engaging the tubular shaft, a detachable pin-and-socket engagement between the spring-pressed member and said dog, a stop, and means for yieldably holding the dog against said stop.

4. The combination with the shaft of an explosion engine, of a tubular crank shaft, a stub shaft carried by said tubular shaft, complementary dogs journaled upon said stub shaft, each having one end positioned to engage the engine shaft and provided with a segmental bearing at the opposite end, a spring-pressed member slidably arranged within the tubular shaft, and a pin carried by said slideable member normally engaging said segmental bearings.

5. The combination with the shaft of an explosion engine, of a tubular crank shaft, a stub shaft carried by said tubular shaft, complementary dogs journaled upon said stub shaft, each having one end positioned to engage the engine shaft and provided with a segmental bearing at the opposite end, a member slidably arranged within the tubular shaft, a pin carried by said slideable member normally engaging said segmental bearings, a spring having one end bearing against said member, and an adjustable abutment for the opposite end of said spring.

6. The combination with the shaft of an explosion engine, of a tubular crank shaft, a stub shaft carried by said tubular shaft, complementary dogs journaled upon said stub shaft, each having one end positioned to engage the engine shaft and provided with a segmental bearing at the opposite end, a member slidably arranged within the tubular shaft, a pin carried by said slideable member normally engaging said segmental bearings, a spring having one end bearing against said member, an adjustable abutment for the opposite end of said spring, and means for locking said abutment in its various positions of adjustment.

7. The combination with the shaft of an explosion engine, of a tubular crank shaft, a stub shaft carried by said tubular shaft, complementary dogs journaled upon said stub shaft, each having one end positioned to engage the engine shaft and provided

with a segmental bearing at the opposite end, a head slidably arranged within the tubular shaft having a shank portion, a pin carried by said head and normally engaging 5 said segmental bearings, a coil spring having one end bearing against said head, a bearing member forming an abutment for the opposite end of the spring and with which said shank has a longitudinal sliding

engagement, the shank projecting beyond 10 said bearing, and a knob in said projection.

In testimony whereof I affix my signature in presence of two witnesses.

WILFRED VALLIER.
